PRETZEL MAKING MACHINE

Harry A. Elliott, Jefferson, Iowa

Application July 9, 1934, Serial No. 734,307

7 Claims. (Cl. 107—8)

In the pretzel industry a considerable loss is occasioned by breaking pretzels when being shipped and handled. This breakage is due, to a considerable extent, to the fact that in many instances the twisted portion is not firmly united and the end portions are not firmly united to the looped portion; and, furthermore, a considerable amount of this breakage occurs when the end portions are permitted to project to a considerable extent over and beyond the looped portion.

The objects of my invention are to provide means of simple and inexpensive construction for tightening the twisted portion of a pretzel when in plastic condition, to such an extent as to cause the twisted portion to firmly adhere, so that when they are later processed and baked the finished product will be bonded at the twisted portion.

A further object is to provide means for holding the end portions of the plastic pretzel firmly against the looped portion at the time that the twisted portion of the pretzel is being stretched, to thereby prevent these end portions from breaking their bonded connection with the looped portion.

A further object is to provide means of simple and inexpensive construction for cutting off the ends of the plastic pretzel which project beyond the looped portion, and for discharging these cut-off ends from the machine.

My invention consists in the construction, arrangement and combination of the various parts of the device, whereby the objects contemplated are attained, as hereinafter more fully set forth, pointed out in my claims, and illustrated in the accompanying drawing, in which:

Figure 1 shows a top or plan view of a pretzel forming plate, means thereon for holding the plastic pretzel to the plate, and a plastic pretzel in position thereon, and by dotted lines illustrating the positions of the pretzel end-cutting knives.

Figure 2 shows a top or plan view of the pretzel end-cutting knives in position for commencing to cut, and in this figure there is illustrated a portion of the pretzel in position relative to the knives.

Figure 3 shows a front elevation, partly in section, illustrating the pretzel supporting plate with a plastic pretzel thereon and the pretzel end-cutting knife in position for commencing to cut.

Figure 4 shows a detail vertical sectional view taken on the line 4—4 of Figure 2 illustrating one of the pretzel end-cutting knives in posi-

tion at the commencement of its cutting movement, and by dotted lines in position after it has thrown the pretzel end away from the pretzel supporting plate.

Figure 5 shows a detail side elevation of a pretzel making machine and illustrating the means for operating the pretzel end-cutting knives; and

Figure 6 shows a detail vertical sectional view through the center of the pretzel supporting plate illustrating means for holding the pretzel loop and pushing upwardly on the twisted portion of the pretzel.

In my companion application, Serial No. 727,702, filed May 26, 1934, I have illustrated and described a pretzel making machine in which there is a continuously moving conveyer with a series of pretzel forming plates thereon, and associated with each of the pretzel forming plates there are means for holding the looped portion of the pretzel in position on the plate and for releasing same at the proper time, so that the finished pretzel may drop by gravity.

In the present application I have used the reference numeral 10 to indicate the conveyor chain on which there is mounted a series of pretzel forming plates, indicated generally by the numeral 11. Carried by the plate 11 is a series of pretzel engaging fingers 12 pivotally mounted below the plate and extending upwardly through slots in the plate. To each of these fingers 12 there is attached a rod 13, and these rods are connected to a head 14 which, at proper times, move downwardly to withdraw the fingers from engaging with the pretzel.

When these fingers 12 are in position shown in Figure 6 they hold the looped portion of the pretzel in position against moving inwardly toward the center of the looped portion and upwardly away from the plate.

The details of this structure are fully illustrated and described in said companion application.

When the pretzel in plastic form is looped around the fingers 12, and twisted, and the ends placed in position over the looped portion, then two presser fingers, which I have indicated generally by the reference numeral 15, engage said ends and direct them downwardly against the looped portion.

The mechanism for operating these presser fingers is also fully illustrated and described in said companion application.

For the purpose of stretching the twisted portion of a plastic pretzel to thereby cause the said twisted portion to firmly adhere to each other

and become bonded, I have provided the following mechanism:

At the central portion of the plate 11 there is a rod 16 vertically arranged to extend through the plate 11 and provided with a second plate 17 at its upper end above the plate 11. This plate 17 is shaped to engage the under surface of the twisted portion of the plastic pretzel resting on the plate 11. On the lower end of the rod 16 there is a roller 18, and the cam shaped guide 19 is fixed to the machine frame in position to be engaged by the roller 18 in its movement with the travelling conveyor. When the roller 18 engages the cam guide 19, the rod 16 will be forced upwardly and the plate 17 will also be forced upwardly to stretch the twisted portion of the plastic pretzel; and since at this time the looped portion of the plastic pretzel will be held against inward movement toward the center of the loop, and the end portions of the plastic pretzel will be held by the fingers 15 against the looped portion, this upward movement of the plate 17 will tend to stretch the twisted portion and cause the parts thereof to be more firmly twisted together, and since the material is in plastic form, the parts thereof will be bonded together.

I have found in practice that, when this twisted portion is thus stretched and firmly bonded, the pretzel may be put through the usual processing and baking operations without separating at the twisted portion.

I have also found in practice that, in making pretzels with my improved pretzel making machine, the pretzel ends will at times, project greater or less distances beyond the loop, due to the fact that the plastic material of which the pretzel is formed is, to some extent, elastic and that this elasticity is affected by temperature and other conditions. It is desirable that the pretzel ends do not project a great distance beyond the loop, because they are easily broken off and the commercial value of the pretzel is thereby impaired.

For the purpose of cutting off these ends at a uniform distance from the pretzel loop under all of these varying conditions I have provided the following mechanism:

The reference numeral 20 indicates the shaft mounted in the machine frame 21, and which shaft drives the endless conveyor. Fixed to this shaft is a cam 22. Mounted in the frame 21 above the upper part of the travelling conveyor is a shaft 23, having a crank arm 24 at one end, provided with a roller 25, which roller engages the cam 22. On the other end of the shaft 23 is an arm 26 to which a spring 27 is connected to hold the roller 25 against the cam 22. Fixed to the shaft 23 is a frame 28. At each end of the frame 28 there is a knife 29 formed with a slot 30, and a set screw 31 extends through the said slot into said frame for adjustably securing the knife to the frame. These knives are normally held by the cam 22 in a position shown by solid lines in Figure 4, so that the pretzel loop will pass under them; then, when the travelling conveyor is being advanced, the cam 22 moves the knives downwardly and in the direction in which the pretzel is travelling, thereby severing the pretzel ends that project beyond the loop; then the cam is also so shaped that, immediately after the pretzel end has been severed, the knives will be rapidly moved to the position shown by dotted lines in Figure 4, and this rapid movement will throw the pretzel ends outwardly beyond the conveyor, in the direction in which the conveyor is travelling, and

these pretzel ends may then be collected in a receptacle 32 located at the end of the travelling conveyor.

In practice with this cutter I have found that the fingers 12 always hold the loop in a certain position relative to the plate, and the fingers 15 firmly hold the pretzel ends against the pretzel loop. Then, when the cam 22 operates to start the knife on its cutting operation, it will always engage the pretzel end the same distance from the pretzel loop, so that the ends will be cut off uniformly, regardless of the amount of contraction and expansion that the plastic pretzel material undergoes while being formed.

I claim as my invention:

1. In a pretzel making machine, the combination of a travelling conveyor shaped to receive and support pretzels in plastic form, a pair of knives, and means operated in unison with the travelling conveyor to move said knives toward and through the pretzel ends and then away from the pretzel at a speed greater than that of the movement of the conveyor, to throw the pretzel ends from the conveyor.

2. In a pretzel making machine, the combination of a travelling conveyor, means thereon for supporting a pretzel in plastic form, a pivoted shaft supported above the conveyor, a pair of knives carried by the shaft, and means operated in unison with the travelling conveyor for moving said knives downwardly and in the same direction as the conveyor is moving, to sever the pretzel ends during the movement of the pretzel, said knife moving means including an element for greatly accelerating the knife movement, after it has severed the pretzel ends, to throw the ends from the conveyor.

3. In a pretzel making machine, the combination of a travelling conveyor, means thereon for supporting a pretzel in plastic form, a pivoted shaft supported above the conveyor, a pair of knives carried by the shaft, a crank arm on the shaft, a cam operatively connected with the travelling conveyor for movement in unison therewith and positioned to operate said crank arm, and a pair of knives on said shaft, said cam being shaped to move the knives first downwardly toward the conveyor and then rapidly in a direction to throw the pretzel ends from the conveyor.

4. In a pretzel making machine, the combination of a plate, means for holding the loop portion of a plastic pretzel upon the upper surface of the plate, and means for moving the twisted portion of a pretzel thus held, in an upward direction to tighten the twist.

5. In a pretzel making machine, the combination of a frame, a plate, means for holding the loop of a plastic pretzel against movement inwardly toward the center of the loop and upwardly, a second plate positioned to engage the twisted portion of a pretzel thus held, and means for moving said second plate upwardly relative to the first to tighten said twisted portion.

6. In a pretzel making machine, the combination of a support, means for engaging the looped portion of a plastic pretzel and holding it stationary on said support, means engaging and holding the free ends of the twisted portion into intersecting engagement with the looped portion and against movement, and movable means for engaging the twisted portion and for stretching the same while thus held.

7. In a pretzel making machine, the combination of a traveling conveyor shaped to receive and support pretzels in plastic form, means for

engaging the looped portion of a plastic pretzel and holding it stationary on said conveyor, means engaging and holding the free ends of the twisted portion into engagement with the looped portion and against movement, movable means for engaging the twisted portion and for stretching the same while thus held, a pair of knives, and means

operated in unison with the traveling conveyor to move said knives towards and from the pretzel ends and then away from the pretzel at a speed greater than that of the movement of the conveyor, to throw the pretzel ends from the conveyor. 5

HARRY A. ELLIOTT.
